UNITED STATES PATENT OFFICE.

ROY R. ALBRIGHT, OF TORRINGTON, WYOMING.

WEATHER-STRIPPING FOR DOORS.

1,178,775.

Specification of Letters Patent. Patented Apr. 11, 1916.

Application filed July 17, 1915. Serial No. 40,463.

To all whom it may concern:

Be it known that I, ROY R. ALBRIGHT, a citizen of the United States, residing at Torrington, in the county of Goshen and State 5 of Wyoming, have invented certain new and useful Improvements in Weather-Stripping for Doors, of which the following is a specification, reference being had to the accompanying drawings.

My present invention relates broadly to new and useful improvements in the construction of doors of houses and similar buildings.

More particularly, the invention has reference to the provision of a novel form of weather stripping for the door.

One of the principal objects of the invention is to construct a door in which the upper and lower edges and outer vertical edge are 20 provided with yieldably mounted weather strips adapted to be projected into engagement with the door casing when the door is closed so that the building or room will be effectively sealed to prevent the entrance of 25 dust, snow, rain, cool air or the like.

A more specific object of the invention is to provide a door having yieldable weather strips and to accompany the weather strip with a projecting means which is of such 30 nature that a single lever may be swung to either project or retract all the weather strip.

The above, and other incidental objects of a similar nature, which will be hereinafter more specifically treated are accomplished 35 by such means as are illustrated in the accompanying drawings, described in the following specification, and then more particularly pointed out in the claims which are appended hereto and form part of this application.

With reference to the drawings, wherein there has been illustrated the preferred embodiment of this invention, as it is reduced to practice, and throughout the several views 45 of which similar reference numerals designate corresponding parts, Figure 1 is a face view of a door constructed in accordance with my invention, the door being partly broken away; Fig. 2 is a fragmentary sectional view through the door, one of the weather strips, and a portion of the door casing; Fig. 3 is a fragmentary detail view, partly broken away, of the lower outer corner of the door to show the auxiliary filling 50 strip.

In taking up the detailed description of

the invention, as embodied in the accompanying drawings, reference will first be had particularly to Fig. 1, wherein the door is best disclosed as an entirety. As shown in 60 this figure, the door designated generally by the numeral 10, is provided in its upper edge with a groove or channel 11; in its hinged, vertical edge, with a groove or channel 12; and in its lower horizontal and outer 65 vertical edges with grooves or channels 13 and 14, respectively. In the channels 11, 13 and 14 respectively, are freely mounted the weather strips 15, 16 and 17, which members are substantially similar in design, each 70 being preferably formed from a bar of wood or equivalent material, accompanied by a facing strip of felt or fabric, as indicated at 18. These weather strips 15, 16 and 17 are adapted to be simultaneously projected into 75 engagement with the door casing or retracted to lie within the channels 11, 13 and 14, by means of a controlling mechanism to be hereinafter described. The channel 12, which is, as stated, formed in the hinged 80 edge of the door, is not continuous, it being necessary to leave portions of the rear edge unchanneled, as at 19 to provide for the attachment of the hinges. Thus, as shown best in Fig. 1 the channel in the hinged edge of 85 the door is formed in three sections, in each of which is mounted a weather strip, as indicated at 20, 21 and 22. These weather strips are normally held in yieldable engagement with the door casing, by means of helical springs 23. A pair of these members 23 is interposed between the rear face of each of the members 20, 21 and 22 and the inner wall of the channel. In controlling the position of the weather strips, 15, 16 and 17, I 90 employ a pair of hand levers 24 and 25 which are respectively disposed against the inner and outer faces of the door and are operatively connected to the members 15, 16 and 17 by a means to be next disclosed. The 100 weather strips 15 and 16, are each accompanied by three bolts of the type illustrated in detail in Fig. 2 while the weather strip 17 is accompanied by four bolts of the same design. These bolts are slidable in the door 105 and are adapted to be projected to move the weather strips into engagement with the door casing. All of these bolts are adapted to be simultaneously projected by either of the levers 24 or 25, one on each side of the 110 door.

Referring now particularly to Fig. 2

- wherein one of the bolt members is illustrated in detail and is shown in connection with one of the weather strips and a portion of the door, it will be seen that the bolt is formed in two sections 26 and 27, the former of which is provided with a head 28, which is seated in a recess 29 formed in the outer face of the weather strip. The section 28 passes freely through the weather strip and into the bore 30 which is formed in the door and extends at right angles to the edge thereof. Within the bore 30 is mounted as shown in Fig. 2 the section 27 of the bolt. The member 26 is provided with an internally threaded bore 31, which receives the reduced threaded extension 32 formed on the outer end of the section 27. Thus the two sections 26 and 27 are detachably and adjustably connected so that the effective length of the bolt may be increased or decreased at will, by rotating the two sections to thread the member 32 farther into the bore 31 or to withdraw it therefrom. A stop pin indicated at 33 is passed diametrically through the section 27 at an intermediate point, as in Fig. 2 and a helical spring indicated at 34 is wound about the section 26 to bear at its forward end against the weather strip and at its rear end against the stop pin. Obviously, the spring acts to yieldably maintain the head 28 of the bolt within the recess 29 and to yieldably hold the weather strip at the outer end of the bolt. The lower edge of the section 27 of the bolt is provided with rack teeth, as indicated at 35. These rack teeth are adapted to mesh with the teeth of a pinion 36, which is rotatable in a receiving recess 37 formed in the door, immediately below the bore 30.
- A pinion 36 accompanies each of the four bolts of the strip 17 and each of the three bolts of the strips 15 and 16. These pinions are keyed upon horizontally disposed axles 38, which are journaled in the door. One end of each axle projects beyond the inner face of the door so that a short lever arm may, as indicated at 39, be applied to the axle of each pinion.
- It will now be apparent that if the lever arms 39 of all of the pinions 36 are simultaneously swung upwardly, the several bolts will all be simultaneously projected and the weather strips 15, 16 and 17 will therefore, be simultaneously projected into engagement with the door casing. On the other hand, if the weather strips are already projected into engagement with the door casing and the lever arms 39 are all swung downwardly below horizontal position, all of the bolts will be retracted and consequently all three weather strips 15, 16 and 17 will be retracted to lie within the channels 11, 13 and 14.
- It is now to be observed that those lever arms 39, which are located at the upper outer corner and the lower outer corner of the

door are L-shaped. These several members 39 are freely connected as shown best in Fig. 1 by means of link rods 40. The lever arms are, of course, slotted so that the terminals of the link rods may be capable of slight movement with respect to the members 39, when the weather strips are being projected or retracted.

The lever arm A, to which the handle 25 is secured, is substantially T-shaped and receives the axle of the pinion to which it is directly connected at the intersection of its right angularly extending portions, as in Fig. 1. The handle 25 is preferably formed as an integral part of the upper end of the vertical portion. The horizontal portion of the member A is connected, as above explained, by the link rods to the lever arms of the pinions of the door.

Referring now to Fig. 1 it will be seen that the handle 25 may be swung to turn the T-member A on its pivot (which is the pinion axle particularly indicated by the numeral 38^a) to simultaneously swing all of the lever arms 39 to cause the simultaneous projection of the weather strips 15, 16 and 17, or may be swung to simultaneously retract all of these weather strips.

In order that the lever arms 24 or 25 may be yieldably retained in adjusted position, I provide for each a contractile helical spring 41 which is secured at its upper end to the lever and at its lower end to the door. The lower end of the spring is in vertical alignment with the pivot 41 so that it will act to hold the lever arm in either of its two positions. A small leaf spring, indicated at 42 is also preferably provided in connection with the lever arms 39 so that these members will be normally held in horizontal position.

In order that the door may be locked when the weather strips are projected into engagement with the door casing, I provide the lock bar 43 which is pivotally attached to the lower end of the member A and is slidably mounted in a casing 44. The bolt is adapted to project into the keeper carried by the door casing for preventing the opening of the door, unless the lever 25 or 24 is swung to retract the weather strips.

It will of course be seen that when the weather strips 16, 17 and 18 are forced outward to engage with the door frame that there will be a space left at the adjacent corners of each pair of weather strips, and in order to close this space at the forward corners of the door I preferably mount between the ends of the weather strips, filling strips 45 disposed in slots in the meeting ends of the weather strips at the forward corners of the door, these strips being extended diagonally toward the center of the door and being formed with teeth 46 adapted to be engaged by pinions 36^a of the same

character as the pinions 36, these pinions 36^a being in turn operated by means of the arms 39 operatively engaging the rods 40 in the manner previously described. It will now 5 be obvious that when the weather strips are projected these corner filling pieces 45 will also be projected and when the weather strips are contracted the corner pieces will also be retracted.

10 What is claimed is:

1. The combination with a door having a longitudinal groove in its upper edge, in its lower edge and in its outer vertical edge, of a weather strip movably mounted in each 15 groove, a plurality of bolts associated with each weather strip, each of said bolts being slidably mounted in the door, a pinion engageable with each of said bolts for projecting or retracting the same, means oper- 20 atively connecting all of said pinions, and means operable from either side of the door for simultaneously actuating all of said pinions whereby all of said weather strips may be simultaneously projected to engage with 25 the door casing or simultaneously retracted to lie within the limits of the grooves.

2. The combination with a door having a longitudinal groove in its upper and lower edges and in its outer edge, and further provided within said edges with inwardly 30 extending bores, of a weather strip disposed in each of said grooves, a sectional bolt movable within each of said bores, a cross pin carried by each bolt, a coil spring on each bolt and disposed between the pin and 35 weather strip, a rack formed on the inner end of each bolt, pinions adapted to engage the racks, means operatively connecting all of said pinions, and means operable from either side of the door for simultaneously 40 actuating all of said pinions whereby all of said weather strips may be simultaneously projected to engage with the door casing or simultaneously retracted to lie within the 45 limits of the grooves.

In testimony whereof I hereunto affix my signature in the presence of two witnesses.

ROY R. ALBRIGHT.
